Figure 3 is an end elevation of the fireplace, the opposite end being a mirror image thereof; and

The figures of the drawing are lined and stippled to represent color contrast.

I claim:

The ornamental design for a fireplace, as shown and described.
